DISPLAY STAND

Frank J. Italiano, P.O. Box 470, La Crosse, Wis.

Filed Mar. 19, 1965, Ser. No. 84,360

Term of patent 14 years

(Cl. D80—10)

FIG. 1 is a perspective view of a display stand showing my design;

FIG. 2 is an elevational view taken from one side thereof, the opposite side being a mirror image of the side shown;

FIG. 3 is a front elevational view of the same;

FIG. 4 is a rear elevational view of the same;

FIG. 5 is a top plan view of the same; and

FIG. 6 is a bottom plan view of the same.

The broken line representation of merchandise, a sign, and the cord that connects them to the stand is for the purpose of illustration only.

I claim:

The ornamental design for a display stand, as shown and described.
